Primary Examiner — Angela J Lee*(74) Attorney, Agent, or Firm* — K&L Gates LLP(57) **CLAIM**

The ornamental design for a recessed lighting fixture, as shown and described herein.

DESCRIPTION

FIG. 1 illustrates a front side view of a recessed lighting fixture.

FIG. 2 illustrates a cross-sectional view of the recessed lighting fixture.

FIG. 3 illustrates a perspective view of the recessed lighting fixture.

FIG. 4 illustrates a perspective cross-sectional view of the recessed lighting fixture.

FIG. 5 illustrates a view of a right side of the recessed lighting fixture; and,

FIG. 6 illustrates a perspective view of a top side of the recessed lighting fixture.

In the drawings, the broken lines represent portions of the recessed lighting fixture that form no part of the claimed design.

1 Claim, 6 Drawing Sheets(56)
